CLAIM

The ornamental design for a wearable band, as shown and described.

DESCRIPTION

FIG. 1 is a perspective view of the first embodiment of a wearable band, showing our new design;

FIG. 2 is an exploded perspective view thereof;

FIG. 3 is a front elevation view thereof;

FIG. 4 is a rear elevation view thereof;

FIG. 5 is a top view thereof;

FIG. 6 is a bottom view thereof;

FIG. 7 is a left elevation view thereof;

FIG. 8 is a right elevation view thereof;

FIG. 9 is another perspective view thereof, showing the wearable band in a state of use;

FIG. 10 is a front perspective view of a second embodiment of a wearable band, showing our new design;

FIG. 11 is a front elevation view thereof;

FIG. 12 is a rear elevation view thereof;

FIG. 13 is a top view thereof;

FIG. 14 is a bottom view thereof;

FIG. 15 is a left elevation view thereof; and,

FIG. 16 is a right elevation view thereof.

The broken lines shown in the drawings illustrate portions of the wearable band and from no part of the claimed design. The other broken lines shown in FIG. 9 are included to depict environmental subject matter only and form no part of the claimed design.

1 Claim, 6 Drawing Sheets
